Primary Examiner — Ricky Pham(74) *Attorney, Agent, or Firm* — Morrison & Foerster LLP(57) **CLAIM**

I claim the ornamental design for a lid for a container, as shown and described.

DESCRIPTION

FIG. 1 is a perspective view of a lid for a container of the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.
